United States Patent Office

Des. 183,675
Patented Oct. 14, 1958

183,675

AIRPLANE

Leon F. Begin, Jr., Pasadena, Welko E. Gasich, Pacific Palisades, George L. Gluyas, Garden Grove, Robert B. Katkov, Burbank, Arthur Nitikman, Los Angeles, and Arthur M. Ogness, Rolling Hills, Calif., assignors to Northrop Aircraft, Inc., Hawthorne, Calif., a corporation of California

Application July 12, 1957, Serial No. 46,920

Term of patent 14 years

(Cl. D71—1)

Figure 1 is a view in perspective of the airplane in flight attitude, showing our new design.

Figure 2 is a front view of the airplane shown in Figure 1.

Figure 3 is a plan view of the same airplane.

Figure 4 is a left side elevational view of the airplane.

We claim:

The ornamental design for an airplane, substantially as shown.
